outh, Mass., a corporation of Massachusetts

Application July 13, 1935, Serial No. 31,217

9 Claims. (Cl. 117—52)

This invention relates to improvements in rope. More especially it relates to the organizing of ropes from vegetable fibres, of which sisal, manila, hemp, etc., are examples, by twisting the fibres into yarns sometimes called threads; those yarns into strands; and the strands into rope.

In the terminology of this specification these several twistings are distinguished in that the twisting of a small bunch of parallel fibres together "spins" a yarn; the twisting of yarns together "forms" a strand; and the twisting of strands together "lays" a rope.

Ordinary ropes have successive reversals of direction of twist, as between yarns, strands and rope. The particular direction in which an element stands spun, formed, or laid, in the completed rope, is herein called the fore-twist direction of the particular element concerned; and the opposite is its back-twist direction, being its direction of untwisting. Tension on the rope tends to untwist the rope, i. e. to untwist the group of strands; but, because of the said reversal of direction of twist as between strands and rope, this twists the more tightly each individual strand of the group; and these harden until finally the untwisting of the rope is stopped by their balancing resistance. This balancing of twists is normal and is the characteristic feature by which a rope holds itself together. But, beyond this balance, the applying of an external and excessive untwisting force to the rope as a whole, sometimes called "back-twisting", or the introducing of back turns, tends to derange the internal structure of the rope, because kinks, nubs and loops form within the strands, and bulge or burst out of them more or less; and this has the general effect that the utility of the rope becomes impaired, its limit of tensile strength reduced, and its working life shortened. The introducing of back-turns can be avoided by expert handling and skilful attention, but many who handle rope are inexpert or careless; and these evil effects are encountered more or less in ordinary handling of rope, especially when that handling is such that turns of the twist are forcibly taken out, as may happen in looping a rope around a bit or cleat, in capstan work, or in coiling. A sizeable rope of finest quality will sometimes be wrecked in a few days of use, by failure of men to observe the precautions which will prevent its being back-twisted.

It is an object of the present invention to produce a rope which may in general have the attributes of a rope of ordinary type, but will be uninjured by such inexpert or careless back-twist-

ing as a rope is likely to experience in ordinary use.

Among the many efforts which have been made to avoid or overcome this difficulty, one with which I have had successful experience provides a septum barrier that inhibits the protruding of yarn kinks, if formed, keeping each in its own part of the rope. This finds its greatest utility in ropes of large size, but is not so advantageously applicable in a small rope. It is therefore another object of the present invention to provide an anti-kink device which can conveniently be built into ropes of relatively small size. The invention accomplishes this for ropes of any size, large or small, having inside yarns, by so organizing the yarns in the strands that the tendency toward the forming of kinks is inherently fore stalled and counteracted, and kinks are much reduced if not entirely prevented.

In one desirable embodiment, my invention would lay the rope with its final twist reverse to that of each strand; and would have formed each strand with twist in direction reverse to the direction of twist of its own exterior yarns; and yarns would fill the strand solidly, each in a helix about the axis of the strand, all as is customary; but the yarns in each strand would vary among themselves in direction of twist and in degree of twist, the exterior or cover yarns of the strand being well twisted; and those yarns standing nearer the axis of strand having degrees of twisting which individually are progressively less in the mathematical sense, step by step, from one course to another, until at the axis the yarns stand well twisted in direction reverse to that of the exterior yarns. The particular effect which the invention seeks is attained in highest degree in a rope structure in which the yarns are relatively large, as compared with customary practice regarding the size of yarns, so that the helixes of fibres which make up the several yarns are as large as may be found advisable after weighing the disadvantages which in other respects attend the use of large yarns.

The making of a rope whose back-twisting would not form kinks has been an aspiration of rope makers for a very long time; but the reactions, conflicts, shifting of stresses and changes of relations which occur within a rope when it is put into a state of strain are so abstruse and confusing that no one hitherto, so far as I am aware, has known the art herein set forth of mastering the kinking evil,—how to apply this art with certainty and at will to ropes of various specifications. Therefore, to perpetuate bene-

ficial advantage of this art I make the following description, setting forth the best modes in which I have contemplated applying the principle.

Each strand of an ordinary or conventional 5 rope structure has a multiplicity of well twisted yarns,—for example fifty or sixty, or considerably less,—filling solidly the cross-section of the strand. One, or a few, of these yarns lies along the axis of the strand; a few lie in a course next 10 to and surrounding those axial yarns; and others lie in courses successively farther from the axis. Each course constitutes a cylindrical sheath which constricts all yarns within it. Each yarn in each course is a helix about the axis of the 15 strand. It is a common practice that all helices of the strand are formed in the same direction of turn about the axis; but sometimes the outer course or courses of yarns run around in direction of turn opposite to the direction of those within. 20 In either arrangement, in a section of strand having a given length, a yarn at the axis has approximately the same length which the axis of the strand has; the yarns immediately surrounding that yarn each have a little greater length; and 25 so on, progressively outward, those yarns which run around the axis at a substantial distance from it having, in any given section of strand, a substantially greater individual linear extent than do those in this same section near the axis.

30 The explanation of the invention can now begin to be seen. The length of each yarn is a function of the pitch and the diameter of its helix, the pitch being the length of axis along which a single convolution of the helix extends. If that 35 said section of strand should be twisted more tightly,—for example, so that one could see by looking at its surface yarns that another half convolution had been introduced,—each of those surface yarns would have been drawn to a steeper 40 angle to the axis, and all would have shorter pitch. As the actual length of each yarn remains unchanged, each yarn could not extend as far as it did along the axis. Each sheath of yarns would 45 have become shorter in its coverage of yarns within it, as well as coming to constrict them more tightly.

The extent of shortening of sheath would be greatest for those yarns which are located at the surface of the strand, for at that distance from 50 the axis each added convolution of yarn requires more length of yarn than is required by a convolution added at a location near the axis.

When a rope is back-twisted the whole of the 55 individual strand experiences the same degree of angular turning, inner yarns like outer yarns; but the consequent shortening of the axial extent of the outer yarns is greater than the simultaneous shortening of axial extent of the inner yarns.

Thus an internal disorganization is promoted, 60 an endwise thrust, of yarns near the axis relative to yarns which surround them. This has to be executed under confused conditions of constriction and friction, which resist it. Flexibility and changing curvature of the rope yarns tend to 65 make a mobile condition somewhat akin to a condition of flux, within the rope, in spite of the tightening pressure; the incompressibility of matter asserts itself; and when the thrust has become strong enough the central elements of the rope 70 find some place to bend laterally, between the surrounding yarns, so as to dispose their growing excess of length, in a loop whose extrusion gives relief. Upon cessation of back-twisting, the extruded disorganized matter does not readily re- 75 sume its proper location. It is held by friction,

and by the presence of local stabilities of twist known as kinks; and if the back-twisting has been severe enough no manipulation is practicable to restore the inaccessible interior parts of the rope to proper form for doing normal work.

The invention provides a combination of helices that gives a measure of relief within the strand. It causes the inner yarns individually to shorten themselves, when the outer helices of yarns shrink because of a tighter twisting of the strand as a 10 whole.

This is accomplished by initially building the strand with the fibres of those yarns which are at and near its axis having their helices as large as is feasible, and by having those fibre helices 15 turn in the direction in which all of the yarn helices turn in the strand. The axial yarns being yarns twisted in one direction, yarns surrounding them concentrically, standing in other courses progressively further from the axis, may be successively of twist diminished, reversed, and increased in reverse direction, the outside yarns having individual twist opposite to that twist with which the assemblage as a whole is being formed 20 as a strand. Strands thus formed may then be 25 twisted into rope, laid with reversal of twist, in the usual way.

With this construction, and assuming the rope to be in its normal condition of internal balance of stresses and parity of relations of its several 30 parts, any back-twisting of the rope will twist each strand more tightly; and the outer yarns therein will tend to make the outer portion of the strand have a shorter linear length, as with conventional ropes hitherto; but that same twisting 35 which shortens and tightens the strand will simultaneously put more turns into the helices of fibres in the yarns near the axis, and this will harden and shorten each of those yarns. Thereby to an extent the interior parts of the strand are 40 shortened simultaneously with the shortening of the outer zone of the strand, thus to an extent reducing the difference and disparity of lengthwise thrust, as between successive courses, which has heretofore resulted in the formation of loops 45 or kinks.

The correction accomplished by the invention is not fully described by the foregoing, because the assumed back-twisting of a rope, with consequent tighter twisting of each strand, involves 50 also a measure of untwisting of each yarn whose individual twist is opposite to the twist of its strand. Therefore, with the shrinkage in length of exterior yarn helices, the fibre helices which compose each of those yarns experience a lengthening which reduces the extent of that shrinkage 55 of those yarn helices. At the same time the interior yarn helices are undergoing a super-shortening, as above described, because of the shortening of their fibre helices. Therefore, with the 60 described diversity and locations of individual twists of yarns, the elements cooperate so as to convert the normal disparity of shrinkages into a sub-disparity, and thus to minimize and defer the effort of interior yarns to protrude.

Because of the inevitable difference in diameter, between the mean helix of fibres in one individual yarn and the mean helix of the course of yarns in which that yarn lies, the differential of length of a yarn, resulting from its individual 70 change of twist when the twist of strand is changed, is not of the same order as is that difference of length of strand surface which is produced by the same twisting of the strand. Therefore a structure embodying the invention may not 75

compensate for the whole of the described disparity. However, it does more than diminish the disparity as above explained, for in addition the beneficial effect is compounded. That harder twisting of the inner yarns which makes them shorter also tends to make them occupy less diameter, and thus to permit the courses of yarns which surround them to settle to a smaller diameter, and therefore to extend themselves to a greater length,—which further reduces the amount of their shortening and of the disparity. In considering the ultimate result one must remember also the characteristic mobility which always exists to some extent inside a rope. Taking this into account, the frontier limit of injurious back-twisting can be made so remote, by proper design on the principles of the invention, that it is not likely to be reached in the ordinary experience of a rope.

When the described gradation of twist of individual yarns extends through several courses, as in Figure 1, it produces in the midst of the strand an intermediate zone wherein are spun yarns whose twist is less hard. These can adjust their shape so as to fill more perfectly all available crannies of space; and this makes it more difficult for the harder twisted units at the axis to find a crevice through which they can extrude themselves.

Details may be simplified, especially in a small rope, by making the gradation have only one step,—all of the yarns surrounded by the cover course having individual hard or soft twist in the direction opposite to that of the cover yarns. The rope would then be made by forming the whole strand with twist opposite to that of the cover yarns; and by laying the desired number of strands together with twist opposite to that of the individual strands.

However, the key to success in combating the kinking evil does not lie in a mere balancing of twists of yarns against each other; and it is not found by considering their proportional numerical division, as, if any particular proportion of the total number of spun yarns were to be chosen of right twist, and the remainder of left twist. The key to success is concerned with the individual sizes in which the yarns are spun; their individual pitch, or amount of twist; the diametric sizes of the helices in which they lie; the diametric location of the cylinder at which the change from one twist to the other occurs; the identity of the direction in which interior yarns were spun, in the making of the yarn, with the direction in which the exterior yarns in the strand are formed, in the making of the strand; and the having of all yarns formed in like direction in the making of the strand, opposite to the twist of strands together in the rope. Best results are attained when the yarns of the exterior course individually have twist contrary to that in which the strand is formed, and all yarns individually have large cross-section, and their fibre helices have short pitch.

The reason why a major elimination of kinking tendency is favored by the use of individual yarns which are large, as compared with spun yarns heretofore used in ordinary practice, is that a change of twist of strand imparts to the mean fibre helix of any yarn in it a greater change of length of helix than the mean fibre helix of a smaller yarn of equal length, in that strand, would experience per equal angular extent of twist. And, further, according to the invention, changes of length of fibre helices in the

yarns cooperate with changes of length of yarn helices in the strand to minimize the disparity,—decreasing the shrinking of helices in the cover yarns and increasing the shrinkage of helices of core yarns.

Rope is made with its surface yarns in small or medium sizes because of better appearance and durability in use. Hence the practical relation may be defined for such ropes by saying that for better anti-kinking effect the interior spun yarns, twisted like the strand, are of sizes larger than the exterior yarns. But whenever a large size is permissible, for the exterior yarns of a particular rope, the tendency of that rope to kink when back-twisted will be still less if also the exterior yarns are of large size. This is because larger cover yarns have greater tendency to extend their length, and so to reduce the net contraction of the exterior helix, upon the occurrence of the back-twisting.

It is intended that the patent shall cover, by suitable expression in the appended claims, whatever features of patentable novelty exist in the invention disclosed.

In the accompanying drawings:

Figure 1 shows a rope embodying the invention, with the end of one strand disclosing a cross-section of the strand; and with the end of another strand laid open which discloses gradation of twists of the individual yarns, from course to course;

Figure 2 is another embodiment of the invention, being a strand having a core and a single cover course of yarns;

Figure 3 is another embodiment of the invention, being a strand with a cover course of yarns smaller than those within;

Figure 4 is a theoretical diagram showing, for a strand of a conventional rope, without benefit of the invention, the relations which the elements of that strand tend to assume, when that strand is twisted more tightly, as by a back-twisting of the rope, i. e. representing the new positions of balance toward which they tend to move, and showing the strain to whose prevention the invention is addressed;

Figure 5 is a theoretical diagram similarly representing the tendency of elements in each strand in a rope of the type of Figure 2, embodying the invention.

The drawings illustrate modes of applying the invention to ropes of three varieties of specification. In Figure 1 the rope 10 is of right lay and each of its three strands 11 is an assemblage of a multiplicity of yarns arranged in courses 20, 22, 24, 26 formed to the left. As thus far described the rope is of ordinary and conventional construction, and each course may have its own individual pitch as illustrated in Figure 1, or all the courses together may be formed as a group all having the same pitch as is indicated in Figures 2 and 3, both types being heretofore known. But a departure from ordinary construction is found in the individuality of twist of the yarns. The outmost yarns are of firm right twist, being those in the outer course 20; and step by step toward the center the hardness of right twist diminishes until, at the axis, it becomes a firm left twist in yarns 26.

Obviously the construction might be reversed in all respects, with equivalent effect; also variations may be made in number and size of yarns and mixtures of sizes and in other details of arrangement on general principles of rope construction, according as the designer of the rope

may choose for serving his purpose and according to the size or other specification for the rope in general, as the invention does not depend upon the rope being of any particular lay or construction, in other respects than those herein particularly set forth. Thus Figure 2 illustrates application of the invention to a smaller rope, of fine yarns wherein, for example, each strand of half inch diameter has a core of about 10 one quarter inch diameter, with five yarns in the core and twenty in the cover, all in the core being of hard or soft left twist individually and all in the cover being individually of firm right twist, and all of both twists, core and cover, as 15 an assemblage, being formed into the strand by twisting all at the same pitch to the left. To make a complete rope three strands such as this would be laid together with right twist.

In Figure 3 a strand is illustrated in which the 20 cover yarns 40 are of ordinary size, for example, 18's, about one eighth inch diameter, but the interior yarns 46 are of larger size, and all are of the same pitch; but the individual yarns at the surface are of right twist and the yarns under the surface course are individually of left twist, as is indicated by the short oblique lines 41 and 47 thereon showing the directions in which the fibres run.

In the strand forming process, when the yarns 30 are assembled under tension and twist, they become distorted from the rotundity produced by their initial twisting, and settle together to fill the strand solidly in shapes like fragments of sectors as indicated; but notwithstanding this 35 distortion and the further distortion by the forming of the yarn into a helix in the strand, and still further by the making of the strand helical in the rope, the fibres in any individual yarn may for purposes of the invention be considered to lie approximately in helices. And when the length 40 of any single complete convolution of a yarn or fibre helix is compared with the length of a single convolution of another helix having equal pitch, and overlying the same part of the axis, it can be seen that the length of single convolution is greater for that yarn or fibre whose helix, 45 considered in cross section, has the greater perimeter.

Making these assumptions, the results of the 50 invention observed by experiment can be confirmed and illustrated by computation; and the structural principles thus validated can be projected into the specifications for ropes of various sizes. Confirmation is had by considering the formula for length of one convolution L , of a helix having diameter D , and pitch H :

$$L = \sqrt{(\pi D)^2 + H^2}$$

Inspection of this confirms that the throwing of 60 an additional convolution into a strand, where there are helices both of larger and of smaller diameter, causes helices having large diameter to undergo greater change of length of helical formation, i. e. length of sheath, than do the helices 65 having small diameter, because, for the larger, the added convolution embodies a greater length of line; and more of the actual length of the yarn or fibre constituting the helix is thus put into the circling part of the helix; leaving less for its progression along the axis. In computing for this 70 demonstration it is sufficient to use round numbers and approximate figures; and it helpful to make a rigid postulate that the diameter of the helix and that the lengths of the yarns in the helix 75 which is being examined remain unchanged. The

actual change in length of that yarn, and its effect, may be considered separately. The effect of introducing a convolution depends upon its pitch and upon the length of section into which it is introduced, but for a one-eighth inch helix at 5 the axis the effect would be to change the length of helix only a few hundredths of an inch.

The operation of the invention can be visualized to an extent by considering the conditions of internal strain which tend toward the making of 10 interior bulges and the bursting forth of kinks, and how the invention reduces these strains. Attention is directed especially in Figures 4 and 5 to the body of material at the axis of the strand, and the body of material comprising the surface 15 course of the strand; the change of length which each of these bodies tends to experience; and the disparity between their changes of length.

Figure 4 is a theoretical diagram illustrating the invention by showing strains which tend to 20 arise within each strand upon the back-twisting of a rope of conventional structure, all of the 25 yarns being formed in like direction within the strand. Figure 4 assumes that a section of strand, initially in a normal state of internal stresses, initially has one of its ends at a plane indicated by the dotted positions 40, 42, 44, 46; the other end in a parallel plane for example, six feet away, each being squarely cross-cut; and makes other incidental assumptions hereinbefore indicated which 30 do not seriously affect the main relations which are under consideration. The dotted lines show the initial position; and the full lines show the changes of position which tend to occur when one additional convolution of twist is introduced into 35 this section.

Assuming the pitch of yarns in the outmost course of the strand to have been initially four and one-half inches, and other yarns to have had pitch about as the drawings would indicate if the 40 external surface of the outmost course had a diameter of one inch; and assuming that the yarn-ends remain unmoved at the remote end (not shown in the drawing) of this six foot section, so that the whole shrinkage is accumulated at the 45 end which is seen in Figure 4, the diagram of Figure 4 can be made. This can be done by computing the length of any one convolution of yarn before and after the introduction of the additional convolution to the section of strand, knowing that the actual length of that section of yarn remains unchanged, although the total number of convolutions therein changes; then finding the new pitch, conforming to the new length of convolution, the diameter remaining unchanged; and then finding the new total length of helix, the 50 new number of convolutions therein being known. Comparison of this with the initial length of helix shows the contraction experienced by the helix which expresses the location of that particular 55 yarn. The change of length of each yarn has then to be found by similar method, for the introduction of the convolution to the strand as a whole applies to each element in the strand.

The pitch of the fibre helices, and the diameter 60 of helices of fibres in the particular yarn being taken, at a proper value, assuming either the external diameter of the yarn or a mean diameter of fibre helices, a computation can be made similarly to ascertain the distance by which the helix 65 of fibres in that yarn tends to lengthen or shorten, and this may be considered to be a measure of the tendency of the yarn itself to extend or to shrink in length. For this computation the 70 working value for perimeter and diameter of the 75

5 fibre helix may be found by assuming the diameter of yarn to be that of a circular yarn having the same area which the yarn actually has in cross-section,—a value which is known because the sizes of yarns are commonly named by their area, to wit, by stating the number of them that can be contained in a tube of known cross-sectional area,—one-half inch, in diameter.

10 The helical course of the axis of the yarn in the strand will ordinarily be a negligible factor in determining the change of length of yarn; and so it will also for determining whether the effect will be pro-kinking or anti-kinking, but if it be desired to measure the extent to which a lengthening or shortening of the yarn affects the shortening of axis of that helix in which the yarn lies, account should be taken of the pitch of the axis of that yarn relative to the axis of the helix in which the yarn lies, in order to determine the 15 value of its projection on said axis of the helix in which the yarn lies.

15 Figure 4, being a diagram thus made on the basis of the assumptions stated, shows that, in order to re-establish the initial state of stresses 20 between fibres, yarns and courses of yarns, the ends of the yarns of the outer course must recede approximately to the position 40'; and that the ends of the yarns in the other courses must move approximately to the positions 42', 44' and 25 46'. Thus the addition of a convolution to the strand, by its excessive shortening of the outer helixes, makes the inner helixes relatively much longer than the outmost helix 40'.

30 In actuality neither end of the strand section moves as represented. The generated tendency to excess of interior lengths is distributed through the section, in slips, strains and stresses of various sorts, and becomes expressed in tighter compressions; in adjustments of internal relations with other yarns; and, if the stress is sufficient, in a lateral bursting out of some of the interior parts in loops and kinks. The introducing of a second additional convolution of twist would more than double the distress caused by the first.

35 Figure 4 represents a strand having yarn sizes and arrangement similar to those of Figure 1, except that it is a conventional strand not embodying the invention.

40 Figure 5 on the same scale as Figure 4 represents similarly by diagram a strand embodying the invention. The interior yarns are of large size, for example, "4's", which means that four of them fill a half inch circular tube; the course around them has 18's as is customary for a wearing surface; making a total diameter of about three-fourths inch, with pitch correspondingly shorter, there being no course having the inch diameter of the outside course in Figure 4. The notably less disparity between length of interior material and length of exterior material 45 illustrates how a rope can have interior yarns and yet have the internal stresses and strains of back-twisting relatively small. They may indeed be made so small, by design in accord with principles of the invention, that the rope is both easy to handle, and is immune from damage caused by such mishandling as rope ordinarily experiences.

45 For the exterior yarns, which have to maintain appearance, resist abrasions and to resist the extrusion of kinks, there has been universal recognition that firm-twisted yarns of size 18's are customary and suitable, and that it is better not to use a larger size. But, with the invention, it appears practicable that both interior and exterior 50 yarns may be 6's or larger, with advantage

and with the saving of cost which is attendant. Being three times the size of 18's they shorten and lengthen more than do the smaller yarns, in case of super-twisting, and so, when set interiorly, they both reduce the tendency for kinks to form. 5 and they make the extrusion of kinks more difficult because of the larger size; and when set exteriorly, their greater lengthening power further reduces the need for their function of resisting kinking extrusion, without failing in their function of providing a practicable wearing surface if the precaution is taken to have them hard twisted.

10 As regards pitch, the anti-kinking effects of the invention are greatest when the rope contains 15 the feature that the pitch of the interior yarns is as short as is feasible, one benefit of which is that with shorter pitch a greater retraction is experienced upon the adding of a convolution. This construction is illustrated in Figure 1, where 20 the pitch of yarns nearer the axis is progressively less than the pitch of yarns more remote.

15 I claim as my invention:

20 1. A rope of spun yarns formed into strands 25 that are twisted together to make the rope, comprising a combination wherein all of the yarns of a strand are formed in like direction of twist; each yarn of the strand being individually twisted, and the individual twists of the inner yarns of the strand are in the said direction in which the 30 yarns are formed, whereby a tendency to a shortening and hardening of the fibre helixes of the inner yarns accompanies any tighter twisting of the strand;

25 2. A rope of spun yarns formed into strands 35 that are twisted together to make the rope, comprising a combination wherein all of the yarns in a strand are formed in like direction of twist; each yarn of the strand being individually twisted, and the individual twists of the inner yarns of the strand are in the said direction in which the 40 yarns are formed, and the twists of the fibres constituting outer yarns are contrary, whereby tendencies to a shortening of the fibre helixes of the inner yarns and a lengthening of the fibre 45 helixes of the outer yarns accompany any tighter twisting of the strand.

30 3. An anti-kinking construction of spun yarns 50 into a rope strand wherein a multiplicity of spun yarns lie in a plurality of courses of yarns formed in helixes, the helixes of one course surrounding the helixes of another course; and wherein the fibres spun in the yarns lie in helixes; all helixes of yarns having twist in a common direction; and all helixes of fibres in yarns of the inmost helix 55 having twist in that same direction; and all helixes of fibres in yarns in the exterior helix having twist in the contrary direction, whereby, when a change of twist in the strand as a whole occurs, disparity of contraction of helixes in the 60 several courses is minimized.

35 4. An anti-kinking construction of spun yarns 65 as in claim 3, in which there are one or more helixes of yarns intervening between said inmost and said exterior helixes of yarns, in which intervening yarns the fibres stand in helixes having twist of a degree intervening between the twists of fibre helixes in said inmost and in said exterior yarns.

40 5. A rope of spun yarns formed into strands 70 that are twisted together to make the rope, comprising a combination wherein all of the yarns in each strand are formed in like direction of twist; each strand having exterior yarns and interior 75 yarns; and each of the said exterior yarns having

individual twist contrary to said forming direction; and each interior yarn having twist individually in the said direction of forming.

- 5 6. A rope of spun yarns formed into strands that are twisted together to make the rope, comprising a combination wherein all of the yarns in each strand are formed in like direction of twist; each strand having exterior yarns and interior yarns; and each of the said exterior yarns having 10 individual twist contrary to said forming direction; and some of the interior yarns having twist individually in the said direction of forming; the exterior yarns individually having size of a character well suited for resisting abrasion, and the 15 interior yarns which are twisted in the forming direction individually having a larger size, whereby they have a character better suited for shortening their several helices when the strand is super-twisted.
- 20 7. A rope of spun yarns formed into strands that are twisted together to make the rope, comprising a combination wherein all of the yarns in each strand are formed in like direction of twist; each strand having exterior yarns and interior 25 yarns; and each of the said exterior yarns having individual twist contrary to said forming direction; and each interior yarn having twist individually in the said direction of forming; the rope being of a type in which yarn sizes 18's or smaller 30 are suitable for all purposes except anti-kinking, but the rope actually being one in which both interior and exterior yarns are individually 6's or larger, whereby the anti-kinking quality of the rope is enhanced as compared with what this 35 quality would be if the same total volume of spun

yarns which compose the rope were made up in sizes of 18's or smaller.

8. A rope of spun yarns formed into strands that are twisted together to make the rope, comprising a combination wherein the yarns lie in a plurality of courses, all formed in like direction of twist in a strand, and the pitch with which the yarns are thus formed is shorter for yarns which stand nearer the axis than it is for yarns which stand more remote from the axis; and the twists 10 of the fibres constituting said yarns which stand nearer the axis being in the said direction in which the yarns are formed, whereby a tendency to a shortening and hardening of the fibre helices of said yarns nearer the axis accompanies any 15 tighter twisting of the strand.

9. An anti-kinking construction of spun-yarns into strands, and of those strands into rope, wherein, in each strand, the fibres of the inmost group of yarns stand spun, in their several yarns, 20 in the fore-twist direction of the forming of their cover yarns in the strand, or in such near proximity thereto that a substantial back-twisting of the rope as a whole would fore-twist them thus; each course of yarns intervening between said inmost group and the exposed cover yarns standing 25 formed in the same said direction, or in the said near proximity thereto, which direction also is the back-twist direction of the rope; the exposed fibres of the cover yarns standing spun with pitch, in their individual yarns, which is less than the pitch in which those yarns stand formed in the completed strand.

CHARLES MACKINNON. 35
